Patented Nov. 14, 1911.

UNITED STATES PATENT OFFICE.

WILLIAM ANDERSON, OF PARKLAND, WASHINGTON.

LOCK.

1,008,883.

Specification of Letters Patent. Patented Nov. 14, 1911.

Application filed March 16, 1911. Serial No. 614,801.

To all whom it may concern:

Be it known that I, WILLIAM ANDERSON, a subject of the King of Norway, residing at Parkland, in the county of Pierce and State 5 of Washington, have invented certain new and useful Improvements in Locks, of which the following is a specification.

The present invention comprises special improvements in locks adapted particularly 10 for use in connection with swinging doors.

The invention embodies particularly a simple form of lock casing carrying a pivoted hasp plate adapted to be engaged with a keeper carried by the frame of the door by 15 proper movement of the plate, locking mechanism being associated with the plate for controlling its operation in the practical employment of the invention.

For a full understanding of the present 20 invention, reference is to be had to the following description and to the accompanying drawings, in which—

Figure 1 is a horizontal sectional view showing a door and frame partially, and the 25 invention being applied thereto, dotted lines illustrating the movement of the hasp plate in being disengaged from the door; Fig. 2 is a front elevation of the locking casing and interior mechanism, the hasp plate being in open position, and certain parts being 30 shown in section; Fig. 3 is a transverse sectional view on the line 3—3 of Fig. 2; Fig. 4 is a longitudinal sectional view on the line 4—4 of Fig. 5; Fig. 5 is a front elevation 35 of the lock; Fig. 6 is a detail perspective view of the sliding bolt; Fig. 7 is a perspective view of the keeper; Fig. 8 is a fragmentary sectional view showing a modified form of keeper.

Throughout the following detail description and on the several figures of the drawings, similar parts are referred to by like reference characters.

In the drawings, 1 denotes the door and 2 45 the frame in which it is mounted. The lock casing is shown at 3 and is screwed or otherwise fastened on the door at the free or swinging portion of the latter. Attached to the frame 2 is a keeper shown more clearly 50 in Fig. 7, and which, for purposes of strength may be constructed of angular form, as shown in Fig. 8. The casing 3 has a base plate 3', and also a covering plate 3'' spaced from the base plate so that a certain portion of the interior of the casing 55 is housed to receive locking mechanism com-

prising the sliding bolt 5, the latter being of somewhat peculiar formation. The bolt 5 consists of inner and outer spaced parts 5' and 5'', respectively, the former being 60 adapted to slide against the base plate 3' while the latter constitutes a locking member coöperating with the hasp plate 6 which is pivoted between its ends as shown at 7 to one end portion of the casing 3. The end 65 portion of the hasp plate 6 adjacent to the pivot 7 has a hook 8 adapted to engage in the opening of the keeper 4, and the opposite end portion of the plate 6 carries the rotatable handle 9 which passes through the 70 plate and has on its inner end a catch 10, movable into and out of engagement with a notch 11 in the casing. The outer locking member 5'' of the bolt 5 has an inwardly extending flange 12 extending therefrom to engage with a guide flange 13 extending longitudinally of the casing 3 and projecting outwardly from the base portion 3' of the latter. The sliding movement of the bolt 5 is limited by means of projections 13' on the 75 member 3', and is effected by means of a key actuated member 14, the latter having a toothed segment 15 normally engaging a toothed rack 16 formed on one edge of the portion 5' of the bolt 5. The key actuated 80 member 14 is provided with notches 17 in its outer side to receive corresponding projections of a key 18 adapted to be introduced into the casing through a suitable key-hole 19 in the hasp plate 6. Projecting from 85 that portion of the member 14 opposite the segment 15 are lugs 20 against which a spring 21 is adapted to bear, coöperation of the parts 20 and 21 being such that the spring will tend to hold the sliding bolt at 90 95 one or the other of its limits of movements. The locking member 5'' of the bolt 5 is adapted to engage a keeper 22 projecting inwardly from the hasp plate 6, whereby the latter may be locked in closed position with 100 respect to the casing, as shown most clearly in Fig. 4 of the drawings.

In the operation of the invention, it will be apparent that to hold the door 1 closed temporarily, the parts may be arranged as 105 shown in full lines in Fig. 1, and also in Fig. 2, the sliding bolt 5 not being in engagement with the keeper 22, but the handle 9 being turned so that its catch 10 engages the notch 11 and holds the hasp plate 6 in 110 closed position. Should it be desired to open the door, the operator turns the handle

9, disengaging the catch 10 from the notch 11 and then swings the hasp plate outwardly into the dotted line position shown in Fig. 1, thus disengaging the hook 8 from the keeper 4 on the door frame, permitting bodily movement of the door. In closing the door, the operation above described is reversed. In order to lock the door from unauthorized opening, the key 18 may be introduced 10 for coöperation with the key actuated member 14, and by turning the latter, the bolt 5 will slide into engagement with the keeper 22 to positively lock the hasp plate from outward movement necessary to disengage 15 the same from the keeper 4.

Having thus described my invention, what I claim as new is:

1. In a lock, the combination of a casing, a hasp plate pivoted thereto and having an 20 engaging hook for coöperation with a suitable keeper, a locking bolt mounted in the casing, a keeper projecting from the hasp plate for engagement with the locking bolt, a handle for manipulation of the hasp plate, 25 and a catch operable by the handle for temporarily holding the hasp plate in a predetermined position.

2. In a lock, the combination of a casing, a hasp plate pivoted adjacent to one end 30 thereof, a keeper projecting inwardly from

the hasp plate, and locking means in the casing comprising a sliding bolt composed of an outer locking member and an inner member, the latter having a rack formed thereon, and the locking member being arranged to coact with said keeper, and a key actuated member in the casing having a segment meshing with the rack aforesaid. 35

3. In a lock, the combination of a casing, a hasp plate pivoted thereto and adapted to 40 close the outer portion of the casing, a handle for manipulating said plate, a keeper projecting inwardly from said plate into the casing, a locking bolt coacting with said keeper and consisting of a locking member, 45 and an inner member spaced therefrom, a key actuated member coöperating with the inner member of the locking bolt to move the latter, a flange projecting from the locking member, and a guide flange projecting 50 from the casing and coöperating with the flange first mentioned to direct the movement of the bolt.

In testimony whereof I affix my signature in presence of two witnesses.

WILLIAM ANDERSON.

Witnesses:
